UNITED STATES PATENT OFFICE

2,593,971

LATCH MECHANISM

Richard J. Brandt, Minneapolis, Minn.

Application October 9, 1946, Serial No. 702,235

1 Claim. (Cl. 292—128)

1

My invention relates to storage receptacles and more particularly to means for securely locking the cover to the receptacle body which can be quickly and easily unlocked when desired.

My invention is particularly adapted to receptacles used for the collection and temporary storage of garbage, rubbish, or the like, and is designed to prevent removal of the cover from the receptacle by dogs or other animals, pranksters or the like, and thus eliminate the untidy appearance and unsanitary conditions which inevitably follow from such removal.

Another object of my invention is the manufacture of a locking means for receptacles capable of the above uses and of accomplishing the above objects which is inexpensive to manufacture, has a minimum of working parts, and is extremely durable in use.

The above and still further objects of my invention will become apparent from the following detailed specification, appended claim and attached drawings.

Referring to the drawings wherein like characters indicate like parts throughout the several views:

Fig. 1 is a side elevational view;

Fig. 2 is a fragmentary perspective view;

Fig. 2 is a fragmentary perspective view; and

Fig. 4 is an enlarged fragmentary view in front elevation taken substantially on the line 4—4 of Fig. 1.

Referring with greater particularity to the drawings, the numeral 1 indicates a conventional open top container, such as a garbage can or the like, which is provided with a removable telescoping cover 2 having a centrally-located handle 3. Cover 2 is also provided with an outwardly-projecting beaded or rolled edge 4. For the purpose of hinging the cover 2 to the open top receptacle 1, and as particularly shown in Fig. 3, I provide a clip-like hinge plate 5 which is secured adjacent the upper open edge of the receptacle body 1 by means of rivets, screws or the like 6. It will be seen that hinge plate 5 has a channel-shaped upper edge 7 which loosely overlies the beaded edge 4 of the cover so as to prevent removal of the cover under straight upward movements while permitting pivotal movements of the same.

Diametrically opposite hinge clip 5, the cover 2 is provided with a hinge bracket 8 which is secured to the side wall of the cover by means of rivets, screws, or the like 9 and which has a pair of outturned ears 10 which are horizontally drilled

2

or pierced to receive a pivot pin 11. Mounted on pivot pin 11 and between the ears 10, is a latch bar 12 which at its bottom outer edge is preferably provided with a plurality of teeth 13 and which is bent inwardly at its upper end to provide a handle 14 overlying the cover 2.

Secured to the receptacle body 1 by means of rivets or the like 15 and immediately underlying the bracket 8, is a latch bracket 16, the upper edge of which is outturned to form a latch plate 17 which is provided with an aperture 18 to receive the toothed lower end of latch bar 12 when the cover is in closed position.

Yieldingly biasing the toothed lower end 13 of the latch bar 12 into engagement with the latch plate 17, I provide a torsion spring, identified in its entirety by the numeral 19 which comprises a pair of coiled portions 20, which loosely encompass the opposite ends of the pivot pin 11, an intermediate portion 21 which bears against the latch bar 12 above the pivot pin 11, and a pair of outer end portions 22 which bear against the cover 2 below the pivot pin 11.

To operate my novel device, it is but necessary to pull outwardly on the inturned handle-equipped end 14 of the latch bar 12 so as to disengage the teeth 13 from the latch plate 17. The cover 2 may then be pivoted upwardly and backwardly so as to permit removal of the contents from the container body 1. When it is desired to close and lock the container against accidental or undesired removal, it is but necessary to again pull backwardly upon the handle 14 so as to permit the toothed lower end of the latch bar 12 to register with the opening 18 of the latch plate 17, at which point, upon release of the handle 14, the torsion spring 19 will force one of the teeth 13 into locking engagement with the latch plate 17.

40 What I claim is:

In a device of the class described, latch mechanism for telescoping covers of garbage cans and the like, including a bracket adapted to be secured to the side edge of said cover, said bracket including a pair of laterally-spaced outwardly-projecting ears, a pivoted pin extending through said ears and terminating outwardly from each thereof, a latch bar pivotally secured intermediate its ends to said pivot pin between said ears, the outer edge of said latch bar adjacent its lower end being provided with a plurality of teeth and the upper end thereof being bent to overlie the upper surface of said cover, a latch bracket adapted to be secured to the side wall of the can immediately below the cover, an upper portion

of said latch bracket being outturned and being provided with an aperture adapted to receive the lower toothed end of the latch bar when the cover is in a closed position, and a torsion spring biasing the toothed lower end of said latch bar toward engagement with the apertured latch plate, said torsion spring including a generally U-shaped member the opposite ends of which are coiled around the opposite ends of said pivot pin.
